(57) **CLAIM**

The ornamental design for a tricycle, substantially as shown and described.

DESCRIPTION

FIG. 1 is a perspective view of a tricycle according to the present invention;

FIG. 2 is a right side elevation view of the tricycle of FIG. 1;

FIG. 3 is a top plan view of the tricycle of FIG. 1;

FIG. 4 is a front elevation view of the tricycle of FIG. 1;

FIG. 5 is a rear elevation view of the tricycle of FIG. 1; and, FIG. 6 is a left side elevation view of the tricycle shown in FIG. 1.

The broken lines, shown as broken/dotted lines, represent those portions of the tricycle that form no part of the claimed design.
